The ornamental design for a candle, as shown and described.

(51) LOC (7) Cl. **26-04**
(52) U.S. Cl. **D26/6**
(58) Field of Search D26/6, 7, 9-11;
431/288, 291

DESCRIPTION

(56) **References Cited**

FIG. 1 is a view in perspective of a candle showing my new
design.

U.S. PATENT DOCUMENTS

FIG. 2 is a top view thereof.

D409,316 S * 5/1999 Majerowski D26/6
D455,846 S * 4/2002 Araujo D26/6
D459,498 S * 6/2002 Araujo D26/6

FIG. 3 is a bottom view thereof.

FIG. 4 is a front view thereof; and,

FIG. 5 is a side view thereof, the front, left side, right side
and rear views all being identical because of the axial
symmetry of the design.
